By Stuart C. Barnes

Attorney

UNITED STATES PATENT OFFICE.

FREDERICK L. LINDHORST, OF DETROIT, MICHIGAN, ASSIGNOR TO DETROIT TORCH & MANUFACTURING COMPANY, OF DETROIT, MICHIGAN, A CORPORATION OF MICHIGAN.

FIRE POT.

Application filed January 16, 1922. Serial No. 529,712.

To all whom it may concern:

Be it known that I, FREDERICK L. LINDHORST, a citizen of the United States, residing at Detroit, in the county of Wayne and State of Michigan, have invented certain new and useful Improvements in Fire Pots, of which the following is a specification.

This invention relates to plumbers' furnaces or fire-pots and has for its object a fire-pot which is provided with a solid grid which permits the burner fuel pipe to be removed from the top of the so-called coil cup or chimney without disassembling the grid from the chimney.

In the drawings,—

Fig. 1 is a vertical cross section of the fire-pot.

Fig. 2 is a plan view of the same.

Fig. 3 is a side elevation of the grid.

Fig. 4 is a perspective of the clamping clip and the fire guard.

a designates what is commonly called a coil cup but which I prefer to call the chimney for the reason that my type of burner does not employ a coil and hence the term is not strictly accurate in connection with my burner.

These coil cups or chimneys have generally been bolted to the grid *b* by such short studs as shown at *c*. Ordinarily in order to take the coil or the fuel pipe out of the chimney it is necessary to unbolt the grid not only from the stud *c* but from the supporting posts *d*. This is somewhat of an inconvenience and it is the object of the present invention to obviate this by the peculiar construction later to be described.

It has been proposed to obviate this difficulty by making a hole in one side of the grid and having a swinging plate or gate to close up this hole. Through this hole the fuel pipe or coil is removable. However, this construction is more or less expensive and is open to the objection that it does not present a solid grid and consequently is liable to warp under the excessive heat that obtains in a furnace of this kind.

The grid *b* is shown in plan view in Fig. 2 and in side elevation in Fig. 3. It will be noticed that on one side of the grid is a deep, depending loop *e*. This permits the fuel pipe *f* to run through the loop and then through the slot *g* in the side of the chimney.

The down run of the fuel pipe connects with

the valve fitting *h* by means of the union nut *i*. Hence by slipping off the usual shield (not shown), and which is held under the shield-retaining lugs *j*, it is possible to lift the fuel pipe and the burner shell *k* out through the top of the grid. Of course, the burner itself designated *m* will first have to be unscrewed in the usual way and removed through the slot *u*. The clip *n*, which is used to clamp the fuel pipe *f* to the burner shell *k* is provided with an obliquely-disposed lug *o* which abuts under the grid and closes the opening through the loop of the grid. This would otherwise permit the fire to shoot out above the fuel pipe through the loop.

I prefer to employ a burner shell *k* in connection with the preheating loop *r*. This is so large that it could not be removed with the ordinary shield-retaining lugs *j*. Hence I have distorted two of the lugs away from each other, as is plainly shown in Fig. 2, for the purpose of permitting clearance between the burner shell and the shield-retaining lugs when the fuel pipe is taken out of the chimney and grid.

What I claim is:

1. In a fire-pot, the combination of a grid provided with a loop in one side, a chimney supported below said grid and having a slot registering with the opening in the loop, and a fuel pipe leading through the opening in said loop and the opening in said chimney and removable from the top of the chimney and grid without disassembling the same.

2. In a fire-pot, the combination of a grid provided at one side with a depending loop having an opening into said loop through the top of said grid, a chimney supported under the grid and having an opening at the side registering with the opening through the loop, and a removable fuel pipe passing through said opening in the loop and which may be taken out of the top of the chimney through the grid without disassembling the two.

3. In a fire-pot, the combination of a grid provided at one side with a loop opening through the top of the grid, a chimney supported under the grid and provided with an opening through its side registering with the opening through the loop, a fuel tank supported under the chimney and the grid, and a fuel pipe having a detachable con-

nection with the tank and having a cross run of the fuel pipe lying in the opening through said loop and passing through the opening in the chimney to the interior thereof, the said fuel pipe being detachable from the tank and removable without disassembling the grid and the chimney by lifting the same out through the grid.

4. A fire-pot, having in combination, a grid provided with shield-retaining lugs having their inner ends distorted, a chimney supported under the grid, a detachable fuel pipe supporting a burner shell within the said chimney, the said chimney and grid being arranged so that the fuel pipe may be lifted out of the same without disassembling them and the said distorted ends of the shield-retaining lugs being suitably di-

rected and distorted to permit the burner shell clearing the same when lifted through 20 the top.

5. A fire-pot, having in combination, a grid provided with a depending and upwardly-opening loop, a chimney supported under the grid and provided with an opening 25 registering with the opening through the loop, a detachable fuel pipe having a cross run passing through the opening in the loop and the opening in the chimney, and a clip supported upon the top of the 30 cross run of the fuel pipe and provided with a guard for engaging under the grid to prevent fire from shooting out from the opening in the loop above the fuel pipe.

In testimony whereof I affix my signature. 35

FREDERICK L. LINDHORST.
